US0D1099534S

(12) **United States Design Patent** (10) **Patent No.:** **US D1,099,534 S**
(45) **Date of Patent:** **** Oct. 28, 2025**

(54) **DUFFEL BAG**

(71) Applicant: **YETI Coolers, LLC**, Austin, TX (US)

(72) Inventors: **Roy Joseph Seiders**, Austin, TX (US);
Erik Steven Larson, Austin, TX (US);
Derek G. Sullivan, Austin, TX (US);
Alex Baires, Austin, TX (US); **Jeffrey Charles Munie**, Austin, TX (US)

(73) Assignee: **YETI Coolers, LLC**, Austin, TX (US)

(**) Term: **15 Years**

(21) Appl. No.: **29/900,419**

(22) Filed: **Aug. 21, 2023**

Related U.S. Application Data

(63) Continuation of application No. 29/846,959, filed on Jul. 20, 2022, now Pat. No. Des. 997,563, which is a continuation of application No. 29/747,996, filed on Aug. 26, 2020, now Pat. No. Des. 958,530, which is a continuation of application No. 29/695,010, filed on Jun. 14, 2019, now Pat. No. Des. 897,102, which is a continuation of application No. 29/634,458, filed on Jan. 22, 2018, now Pat. No. Des. 853,115.

CLAIM

The ornamental design for a duffel bag as shown and described.

DESCRIPTION

FIG. 1 is a top, front, right perspective view of a duffel bag showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate portions of the duffel bag and form no part of the claimed design.

1 Claim, 6 Drawing Sheets
